CENTER FILLING FORK LOOM
ATTACHMENT

Walter B. Gallant, Jr., Lowell, Mass., assignor to
Newmarket Manufacturing Company, Lowell,
Mass., a corporation of Massachusetts

Application February 16, 1942, Serial No. 431,009

5 Claims. (Cl. 139—228)

This invention relates to automatic looms of the Draper type in which there is a magazine or battery for bobbins with bobbin transfer mechanism. In this type of loom there is a filling feeler which engages the bobbin, or the yarn wound thereon, in a shuttle, in such a manner that when the filling on the bobbin is near exhaustion, the feeler initiates action whereby a full bobbin replaces the almost empty one in the shuttle.

Such devices are shown in patents to Brown, Nos. 1,593,426 and 1,599,806.

Some of these looms have side fork filling feelers but this invention applies to those having a center fork filling feeler of the type shown in patent to Lindsjo, No. 1,865,930. The purpose of this is to indicate a broken pick or filling thread and to set or start mechanism to stop the loom. The magazine filling feeler is not intended to stop the loom but is intended to replace a nearly exhausted bobbin with a full bobbin while the center fork filling feeler is intended to stop the loom when there is a broken filling thread.

In such a loom, the center fork filling feeler stop motion includes a fork located near the middle of the lay and made up of prongs carried by a prong holder pivoted on a bracket and carrying a crank shaft which moves with the prongs. In normal operation, the prongs are held up by the filling thread which passes under them but if this thread sags or breaks, the prongs and the crank shaft drop down a certain distance.

However, with certain kinds of yarn especially silk, rayon or fine cotton, on the first pick after transfer, when the shuttle with the new full bobbin is first picked, there is a tendency to slackness which is sufficient to allow the center filling feeler fork to drop and stop the loom.

The object of this invention is to put the center fork filling feeler out of action only during that particular pick and to allow it to resume operation immediately thereafter.

I accomplish this by one or two simple connections between the mechanism for transferring the bobbins and the center fork filling feeler mechanism for stopping the loom when there is a broken or a slack pick.

For convenience in this specification, the word "front" means that part of the loom where the cloth beam is located and "back" that part where the warp beam is located. The term "forward" means moving towards the front and "backward" means moving towards the back. It is assumed that the magazine or battery is on the right of one facing the front of the loom and looking toward the back, and that left is the opposite side. The word "indicate" or "indication" applied to the filling or bobbin transfer mechanism means setting in action the devices for transferring a bobbin, and as applied to the center filling feeler fork,

means setting in action mechanism for stopping the loom when the filling breaks or is too slack.

In the drawings, Fig. 1 is an isometric view looking generally from the front towards the back, showing the principal parts of an automatic loom of the type to which my device is attached.

Fig. 2 is a front elevational view of a center filling feeler fork of a well known type such as shown by Lindsjo, No. 1,865,930 with its connections.

Fig. 3 is an elevation showing the connections from the transfer filling feeler to the mechanism for setting the transfer devices.

Fig. 4 is a side elevation of the bunter, knock off plunger arm, cam and slide rod and other parts in their normal position during the running of the loom.

Fig. 5 is a view similar to Fig. 4 but showing the knock off plunger arm and cam lifted so that the arm clears the bunter, this being the position of the parts when my device operates to lift the arm out of the path of the bunter.

Fig. 6 is an isometric view of certain well known parts which connect the starting rod with the bobbin transfer mechanism.

Fig. 7 is a side elevation of my knock off plunger locking lever moving member in its normal position while the loom is running, with its lower jaw resting on the free end of the locking lever.

Fig. 8 is a view similar to Fig. 7 but showing the lower jaw of my locking lever moving member resting on the shipper stand instead of on the free end of the locking lever.

Fig. 9 is an isometric view looking from the back toward the front and showing the details of the transfer feeler which controls bobbin transfer and its connections as well as the locking lever, its holding hook and my locking lever moving member, the parts being shown in the normal running position of the loom.

Fig. 10 is a plan view of the shipper stand with the knock off lever, the slide guide cam locking lever and my locking lever moving member together with the shipper handle and other related parts with which my locking lever moving member is associated.

Fig. 11 is a sectional elevation as from the right of line 11—11 on Fig. 10 with parts broken away for clearance, the parts being shown in full lines as they are while the plunger arm is held above the bunter during transfer and in dotted lines in the position the parts assume when my locking lever hook and moving member are released and the slide guide cam and locking lever are about to return to their normal positions, the returning spring for the plunger rod being omitted.

Figs. 12A and 12B are diagrams showing the position of the shuttle on what might be called

the transfer pick and the first pick after transfer.

Applicant's improvement is designed for use on a Draper loom or loom having a battery and filling changing devices similar to those shown in the Brown Patents Nos. 1,593,426 and 1,599,806 and having devices for detecting a break or slackness in the filling at or near the center of the lay and to stop the loom, similar to those shown in patent to Lindsjo No. 1,865,930. Such old structures and other old loom constructions are no part of my invention.

The following center filling fork mechanism parts are similar to those shown in patent to Lindsjo No. 1,865,930.

Referring to Figs. 1 and 2, F is the stationary frame and L is the lay which carries the center fork crank shaft 38. Attached to center fork knock off rod 30 is a center fork cam 31 with the usual spring 32 and knock off collar 33. The knock off rod 30 is reciprocated by a push rod 35 reciprocated by devices 34 from a filling cam A of a well known type such as shown by Lindsjo.

This center fork knock off rod 30 causes the center fork cam 31 to reciprocate and also causes the center fork bunter K to reciprocate transversely while the loom is running except when there is a slack or broken filling thread T which allows the center fork crank shaft arm 36 to drop into a recess 37 in the center fork cam 31.

When this happens, the parts are so timed and positioned that the center fork bunter K is held in such a position that, as the lay moves forward, it will engage a center fork knock off plunger arm B carried by a holder 40 at the end of a knock off plunger rod 41, Figs. 4 and 5, which passes through a slide or guide 43, which includes a cam part 42, and is pivoted at 141 to a knock off lever D.

I will call this combination a slide guide cam as it serves several purposes. It is carried by one end 104 of locking lever 11 movable horizontally on a vertical pivot on shipper stand 14 as shown in Figs. 4, 5, and 10.

The other end 102 of locking lever 11 extends normally under the finger 101 of locking lever holding hook 10 as shown by the full lines in Fig. 7.

The slide guide cam 43 is slideable on knock off plunger rod 41 without holder 40 and arm B, there being a slide cam spring 44 to keep the slide guide cam 43 out in contact with the holder 40.

The front end 45 of the knock off plunger rod 41 as shown in Figs. 4, 5, and 10 is pivoted to one end 141 of knock off lever D, the other end of which is held against shipper handle 13 and against loose motion by a spring 20 while knock off lever D is pivoted to the filling motion shipper stand 14 at 142 as shown in Fig. 10.

A locking lever holding hook 10 is pivoted to stand 14 and has an arm 100 which extends down at about a right angle opposite to a trip member 21 carried by the lay L while its finger 101 normally rests on one end 102 of locking lever 11 pivoted to the stand 14. The shipper spring 20 is preferably attached to this locking lever holding hook 10 in such a way that while hook 10 is normally kept down by gravity, it is prevented from rattling by the spring 20.

When the filling under the prongs of the center fork C is loose or broken, the bunter K engages the plunger arm B and as the lay L moves forward, the knock off plunger rod 41, slide guide cam 43, filling motion knock off lever D and

shipper handle 13 are so moved as to stop the loom and, at the same time, the other or free end 102 of the locking lever 11 slips under the finger 101 of the locking lever holding hook 10 which finger drops in front of end 102 so that hook 10 holds these parts in the loom stopped position until the loom is started manually. See Fig. 8.

It is found that, especially with silk, rayon and other fine goods, on the first pick after transfer where the thread from the new bobbin in the shuttle is held outside of the selvage, there is a tendency for this thread, after transfer as it passes under the center fork, to be loose thus allowing the center fork crank shaft 36 to drop and engage the cam recess 37 thus holding the bunter K in position to engage plunger arm B and thus to stop the loom.

The purpose of my device is to provide mechanism which will come into action only before, during and after the first pick after transfer whereby the slide guide cam 43 with the knock off plunger rod 41 and plunger arm B will be lifted out of the way of the bunter K while the lay is moving from bottom to front center and the loom will not be stopped and so that after such pick, these parts will go back into place and continue to function to stop the loom whenever at any other time there is a looseness or break on any pick except this particular first pick after transfer.

I utilize the fact that when the slide guide cam 43, with its cam part 42, is moved back by holder 40 and rod 41, being pushed back by bunter K or in any other way, it passes over a pin 80 fixed to the stand 14 which causes the holder 40 and plunger arm B and that end of the knock off plunger rod 41 to rise out of the way of the bunter K.

Broadly speaking, I accomplish my purpose by providing a pin P in the locking lever holding hook 10 to which I attach one end of the shipper spring 20, together with a knock off plunger locking lever moving member M which I pivot at one end to an elongated starting rod arm stud 17 which also serves as a pivot for the filling feeler slide 3 all being carried by the starting rod arm 16 which is moved forward when transfer filling feeler 18 moves rod 1, and lifting lever 2 pivoted to slide 3 to engage the vertical arm of filling cam follower trip 4 as shown in Fig. 3 in a manner similar to the filling transfer mechanism shown in patent to Brown No. 1,599,806.

Locking lever moving member M has an upper jaw 83 and a lower jaw 84 forming a mouth 85 which goes around the locking lever holding hook pin P, which projects from locking lever holding hook 10. Lower jaw 84 normally rests on free end 102 of the locking lever 11 except when this lever moving member M is moved forward by the action of the transfer filling feeler 18 and rod 1 in locking together the parts 2, 3, and 4, Figs. 3, 9, 10, so that the transfer filling feeler slide 3 and the starting rod arm 16 with its stud 17 are moved forward from the full to the dotted line position in Fig. 10 thus turning starting rod 50 and setting the old and well known parts 51, 53, 54, 55, 56, 57, 58, and 59 for transfer. When stud 17 is thus moved forward to the dotted line position in Fig. 10, the lower jaw 84 of this lever M drops in front of free end 102 of the locking lever 11, as shown by the dotted lines in Fig. 7 and during transfer, jaw 84 of moving member M moves end 102 back to the full line position in Fig. 8. This backward movement of end 102

causes the other end 104 of locking lever 11 and the slide cam 43 to move forward and up over pin 80, Fig. 5, but without moving the knock off plunger rod 41 forward and therefore without stopping the loom. See Figs. 4, 5, 6, 7, 8, and 11.

Without my locking lever moving member M and connections, when there is a loose or broken pick after transfer, the center filling fork C causes or permits the bunter K to engage arm B of the knock off plunger 41 and the knock off lever and shipper handle therefore stop the loom on the next pick after transfer.

The filling transfer mechanism is an old and well known type similar to what is shown in patent to Brown No. 1,599,806 of September 14, 1926.

In Fig. 9, I show the well known arrangement of filling transfer feeler 18 with feeler rod or actuator 1, cam follower trip 4, which is constantly reciprocating by means shown in Fig. 1, and has a vertical arm proximate slide or actuator 3 which on indication of transfer is locked to trip 4 as shown in Figs. 1, 3, 9, and 10.

In Figs. 1, 10 and 11 are shown the connections through arm 16 to starting rod 59 and in Figs. 1 and 6 are shown the connections between starting rod 58 and transfer hammer 59.

These parts are well known and are similar to those shown by Brown, No. 1,599,806. They include the bunter 56 on the lay and the dog 55 carried by the transfer hammer 59 together with the shuttle feeler protector device 54 attached to sleeve 53 which is carried by arm 51 on rod 50 and is normally held down by spring 52, Fig. 6.

With the shuttle at the left or on the side away from the battery, the transfer feeler feels an almost empty bobbin and through the feeler rod or actuator 1 lifts the lifting lever or operating member 2 which is pivoted to the feeler slide or actuator 3 into a notch or opening in a housing in the vertical arm of the filling cam follower trip 4. The lay moves back but, at the same time, the parts are so adjusted that the end of the vertical arm of trip 4 has entered the slot in the feeler slide or actuator 3 and as that arm moves toward the front of the loom, it forces the filling feeler slide or actuator 3 forward. This moves the starting rod arm 16 and sets the transfer mechanism for transfer. The lay continues back and then forward and this motion causes the transfer of the bobbin and resets all the parts so that on the next pick after transfer, without my locking lever moving member M, if there is a slackness in the filling, the center fork will stop the loom.

Figs. 12A and 12B are diagrams showing the timing of different movements. The front is at the left and the back is at the right and the crank movement is clockwise as shown by the short arrows. For convenience, starting at bottom center at X, 12A, with the shuttle on the side away from the magazine, indication of near exhaustion of filling would be in the sector marked I and at the end of indication between front, top and back centre, the parts 4, 3, and M, Figs. 3 and 10, move forward or from back B to front F as shown by the arrow, Fig. 12A and from the full to the dotted line position in Figs. 7 and 10. Between top, back and bottom centre, the shuttle is moving toward the magazine side and forward, this being the transfer pick.

The transfer is accomplished in the sector marked T, Fig. 12B and when this is about finished, 4, 3, and M move back as shown by the long and short arrows so that at back centre, M

has moved 102 thus lifting B above K, Fig. 5, and allowing hook 10 to drop into the locking position shown in Fig. 8. The shuttle in the meantime is moving during top, back and bottom centre, as the first pick after transfer, from the magazine side to the off magazine side past the inoperative center filling feeler fork "C F" which as shown by the line of dashes remains out of action until, as shown in Fig. 12B, between bottom and front centre at the dotted sector marked R, locking lever holding hook trip member 21 engages arm 100 thus raising hook 10 and locking lever moving member M, as shown by the dotted lines in Fig. 11, thereby allowing all the center filling feeler parts to resume their usual positions.

My purpose is to keep knock off plunger rod arm B out of the way of bunter K while the shuttle is traveling past the center filling feeler fork C until hook 10 and member M release locking lever 11 whereupon spring 44 moves 43 back from pin 80 thus allowing B to drop in front of K, Figs. 4 and 5.

As on the backward motion of the lay L, the vertical arm of trip 4 moves forward and sets the transfer, locking lever moving member M goes forward with starting rod arm 16 and slide 3 whereupon its lower jaw 84, as shown by dotted lines in Fig. 7, slips off the top of the end 102 of locking lever 11 so that the back edge of the jaw 84, on the next forward motion of the lay which causes transfer, pushes that end 102 of locking lever 11 back as shown in Fig. 8, and its other end 104 with the slide guide cam 43 forward thus lifting the slide guide cam 43 up on to pin 80 where it rests. This also lifts plunger rod 41 and arm B, Fig. 5. At the same time, the finger 101 of hook 10 drops in front of that end 102 of the locking lever 11 and holds it, with the rest of the slide guide cam 43, rod 41 and rod arm B and other parts, so that the arm B is up out of the way of the bunter K during that pick, which is the first pick after transfer, except as described and shown at sector R while the lay goes back and then forward.

On this pick, when the lay comes forward after the shuttle has been picked across, the locking lever holding hook release screw or trip member 21, Fig. 11, on the lay hits the downwardly extending arm or end 100 of the hook 10 and this kicks up its other end with pin P, thus releasing locking lever 11 and locking lever moving member M both of which are returned to their normal positions by the shipper spring 20 and by compression spring 44 which surrounds the plunger rod 41. See Fig. 10.

The upper jaw 83 of locking lever moving member M is so shaped and positioned that when pin P is kicked up with hook 10, it engages and lifts jaw 83 and also jaw 84 from in front of free end 102 of locking lever 11 allowing the locking lever 11 and slide guide cam 43 to return to normal position. Lower jaw 84 and hold down spring 87 keep locking lever moving member M from flying up too far but spring 87 can be omitted and spring 20 might be omitted as far as its purpose is to hold down hook 10 because gravity alone would return it and member M to their normal positions.

When rod 50 turns lifting arm 51, the dog 55 is moved into position to be engaged by bunter 56 to effect transfer. Spring 58 on the transfer has the usual well known function of returning the transfer hammer to normal position when released and spring 52 resets the protector device

54 and slide 3. This causes stud 17 and member M to move free arm 102 back and slide guide cam 43 forward. This holds plunger rod arm B out of the way of bunter K, until the new bobbin is picked across laying the filling in the center fork. Upon the next forward movement of the lay, 21 hits 100 as shown in Fig. 11.

The essence of my invention is the locking lever moving member M which is of such a kind and is so attached to some movable member of the bobbin transfer devices that during transfer it so engages some part of the center filling feeling devices as to prevent them from stopping the loom during the first pick after transfer. As shown, it is released by pin P in the locking lever hook 10 but it might be released by some other connection to locking lever hook 10 or to some other part of the machine.

I claim:

1. In an automatic bobbin-changing magazine loom including a stationary frame with a shipper stand fixed thereto, a shipper handle to stop the loom and a knock off lever pivoted to the shipper stand and engaging the shipper handle, a forwardly and rearwardly reciprocating lay, bobbin transfer devices including a starting rod arm pivoted on the frame which arm is moved toward the front when the transfer mechanism is set and toward the back during transfer together with a center filling feeler fork and stop motion devices including a bunter on the lay and devices to reciprocate it transversely, a knock off arm carried by a plunger rod pivotally connected to the knock off lever, the plunger rod passing through a slide guide cam having a downwardly projecting cam face and being carried by one end of a locking lever pivoted on the shipper stand upon the free other end of which locking lever rests the holding finger of a holding hook, which hook is pivoted to the frame, the slide guide cam being slidable on the plunger rod over a slide guide cam follower pin fixed to the shipper stand, and a returning spring for the slide guide cam and the locking lever; the combination of said holding hook; and starting rod arm; with a lifting pin extending transversely through the holding finger of the holding hook; a locking lever moving member pivoted at one end to the starting rod arm and at the other end having a mouth with a lower jaw which rests on the free end of the locking lever and an upper jaw which extends over the lifting pin in said hook; and a hold down spring to keep the holding hook and locking lever moving members in position.

2. In an automatic bobbin-changing magazine loom of the class described which includes loom stopping mechanism operable by a center filling feeler fork, a locking lever and a holding hook to lock the loom stopping mechanism in inoperative position when the loom is stopped by the center filling feeler fork, and transfer filling feeler devices which include a member movable from back to front on indication of near exhaustion of thread on a bobbin in a shuttle; a locking lever moving member so attached to the movable member as to so move the locking lever that the holding hook and the locking lever lock the loom stopping mechanism in inoperative position during part of the first pick after transfer; and means to release the hook and latch after that pick.

3. In an automatic bobbin-changing magazine loom of the class described which includes loom stopping mechanism operable by a center filling feeler fork, and means to lock the loom stopping mechanism in inoperative position when the loom

is stopped by the center filling feeler fork, and transfer filling feeler devices which include a member movable from front to back on indication of near exhaustion of thread on a bobbin in a shuttle; a locking lever to lock the loom stopping mechanism so operable by the transfer filling feeler devices as to move the loom stopping mechanism and to lock it in inoperative position during part of the first pick after transfer; and means to release the loom stopping mechanism after that pick.

4. In an automatic bobbin changing loom having a frame and a lay, of the class described, which includes loom stopping mechanism operable by a center filling feeler fork, and transfer filling feeler devices to replace bobbins in a shuttle, which devices include a member movable from back to front on indication and near exhaustion of thread on a bobbin in a shuttle and from front to back on transfer; the combination with a locking lever including a hook pivoted to the frame near one end and having a releasing arm at that end and a holding finger at the other end, which finger normally rests on the locking lever, to lock the loom stopping devices in inoperative position when the loom is stopped by the center filling feeler fork; of a pin extending into the holding finger of the hook; and a locking lever moving member pivoted at one end to the movable member of the transfer filling feeler devices and at the other end having a mouth with a lower jaw which rests on the locking lever and an upper jaw which extends over the pin of the holding finger of the locking lever hook whereby on indication for transfer, the locking lever moving member is so moved by the movable member of the loom stopping mechanism that during transfer it moves the locking lever so that the holding finger of the hook drops into position to hold the locking lever and the loom stopping mechanism in inoperative position during part of the first pick after transfer; and means to engage its arm and to release the hook from the locking lever after that pick.

5. In an automatic bobbin changing loom having a frame and a lay, of the class described, which includes loom stopping mechanism operable by a center filling feeler fork, and transfer filling feeler devices to replace bobbins in a shuttle, which devices include a member movable from back to front on indication and near exhaustion of thread on a bobbin in a shuttle and from front to back on transfer; the combination with a locking lever including a hook pivoted to the frame at one end and having a holding finger at the other end, which finger normally rests on the locking lever, to lock the loom stopping devices in inoperative position when the loom is stopped by the center filling feeler fork; of a pin extending transversely through the holding finger of the hook; and a locking lever moving member pivoted at one end to the movable member of the transfer filling feeler devices and at the other end having a mouth with a lower jaw which rests on the locking lever and an upper jaw which extends over the pin of the holding finger of the hook whereby on indication for transfer, the locking lever moving member so moves the locking lever that the holding finger of the hook drops into position to hold it during part of the first pick after transfer; and means to release the locking lever hook from the locking lever after that pick.

WALTER B. GALLANT, JR.
